UNITED STATES PATENT OFFICE

GARRETT G. DEIDRICK, OF KENT, OHIO

COLLAR-STIFFENING AND TIE-HOLDING DEVICE

Application filed January 25, 1929. Serial No. 335,103.

This invention relates to devices for reinforcing collars and holding ties.

The general purpose of the invention is to provide a device adapted to cooperate with channels in the back of and adjacent the front edges of the outer collar fold effectively to reinforce said edges, and provided with means thereon for reinforcing the crease of the collar adjacent the front end means for holding the necktie in place also effective by adjusting of the tie to draw the front edges of the collar inwardly toward the collar band and to prevent the same from spreading.

A further purpose of the invention is to provide a device such as described above which is of single thickness material whereby bulkiness will be avoided.

The foregoing and other purposes of the invention are attained in the device illustrated in the accompanying drawings and described below. It is to be understood that the invention is not limited to the specific form hereof shown and described.

Of the accompanying drawings,

Figure 1 is a front elevation of a collar illustrating the reinforcing and tie-holding devices embodying the invention in place therein;

Figure 2 is an inside plan of a portion of the collar with the folds flattened out;

Figure 3 is a section on line 3—3 of Figure 1;

Figure 4 is a detail elevation of the reinforcing and tie-holding device per se; and

Figure 5 is an edge view thereof.

Referring to the drawings, the numeral 10 designates a soft collar which is provided with channels at 11, 11, in the back of its outer fold adjacent the front edges thereof for receiving the reinforcing and tie-holding devices embodying the invention.

These devices are made substantially as shown in Figure 3 of comparatively thin material or materials in combination, such as celluloid, hard rubber, sheet metal wire, vulcanized fibre, etc., preferably sufficiently pliable as to be adapted to the curvature assumed by the collar when in use, and which are formed with a leg 12 for insertion into a channel 11, and with a wing 13 for extend-

ing under and reinforcing the major crease 14 of the collar adjacent the front edge, the upper edge of the wing preferably being curved inwardly as at 13^a to be adapted to the collar fold. The wing is provided with a depending loop 15 through which the tie 16 is passed, this loop preferably being open as shown and preferably being in practically the same plane with the leg and wing of the reinforcing device, excepting from a rearwardly off-set portion at 15^a designed to facilitate passing the tie outwardly through the loop.

It will be apparent that the device is easily assembled with or removed from the collar. While the collar is open, as shown in Figure 3, the tie is passed through the loops as illustrated. The collar is then folded and placed about the neck and buttoned. The tie is next adjusted, it sliding easily through the loops 15, and as the knot is tightened against the neck, the action of the tie on the loop 15 draws the front edges of the collar inwardly toward the collar band and interlocks the collar and tie in such a way that both are held in their proper positions. The tie through cooperation with the loops 15 prevents spreading of the front edges of the collar. The legs 12 prevent buckling of the front edges of the collar and the wings 13 prevent buckling of the major crease of the collar at the front.

It will be seen that by drawing the tie through the loops in the manner shown, the inward action of the tie is effective on the sides of the loops adjacent the legs and thus is substantially directly effective on the legs without having any tendency to rock or twist the reinforcement.

As is apparent from the foregoing, a simple and inexpensive, but effective device has been provided for stiffening collars, holding the necktie in position and preventing the collar fronts from spreading. The device, of course, may be applied either to the soft or semi-stiff collars and is more especially adapted to collars of multiple-ply construction.

What is claimed is:

1. A device of the character described

comprising comparatively stiff members including a leg portion for fitting into a channel in back of and adjacent the front edge of a collar to stiffen said edge, a wing portion extending from the leg portion rearwardly under the major crease of a collar to prevent buckling of said crease, the upper edge of said wing portion being curved rearwardly, and a loop depending from the wing portion, the side of the loop remote from the leg being open and the side of the loop adjacent the leg having a rearwardly off-set portion thereon, and through which loop the tie is passed whereby the adjustment of the tie acting in said off-set portions of the loops draws the front edges of the collar inwardly toward the collar band and the tie holds the front edges against spreading.

2. A device of the character described comprising comparatively stiff members including a leg portion for fitting into a channel in back of and adjacent the front edge of a collar to stiffen said edge, a wing portion extending from the leg portion rearwardly under the major crease of a collar to prevent buckling of said crease, and a loop depending from the wing portion, the side of the loop remote from the leg being open and the side adjacent the leg being rearwardly off-set and through which the tie is passed whereby the adjustment of the tie draws the front edges of the collar inwardly toward the collar band and the tie holds the front edges against spreading.
